No. 708,431.

F. W. WALKER.

Patented Sept. 2, 1902.

BED FRAME.

(Application filed Oct. 5, 1900.)

(No Model.)

UNITED STATES PATENT OFFICE.

FREDERICK W. WALKER, OF UTICA, NEW YORK.

BED-FRAME.

SPECIFICATION forming part of Letters Patent No. 708,431, dated September 2, 1902.

Application filed October 5, 1900. Serial No. 32,181. (No model.)

To all whom it may concern:

Be it known that I, FREDERICK W. WALKER, a citizen of the United States of America, and a resident of Utica, Oneida county, New York, 5 (whose post-office address is Utica, Oneida county, New York,) have invented certain new and useful Improvements in Bed-Frames, of which the following is a specification.

My invention relates to a stretcher device 10 for stretching woven-wire mattresses on beds; and it consists in the combination and arrangement of the parts, as hereinafter more fully pointed out and claimed.

The object of my invention is to furnish a 15 cheap, strong, and reliable stretcher device for stretching woven-wire mattresses on metallic beds, whereby the tautness of the wire fabric is under the control of the stretching device, and the hanger or coupling-iron which 20 attaches the side rails of a metallic bed to the bed-posts, which are preferably tubular in form, is illustrated in a patent issued to me, No. 653,158, July 3, 1900, and will not be particularly described. By referring to this 25 patent I do not, however, limit or in any manner circumscribe the utility of my invention to beds having such hangers, because my device can be used with any form of hanger which will maintain the side rails in contact 30 with the tubular bed-post.

Referring to the accompanying drawings, Figure 1 is a top plan view of the end portions of a side rail and portions of the cross-bars, the woven-wire fabric not being shown. 35 Fig. 2 is a side elevation of the structure shown in Fig. 1, the woven-wire fabric being indicated by a heavy line and the said fabric and side rail being shown partially broken away. Fig. 3 is a detail plan view of one of 40 the slides. Fig. 4 is a detail end view of the slide shown in Fig. 3. Fig. 5 is a detail top plan view of one of the coupling-hangers at the end of the frame at which the adjustable cross-bar is located, the tubular bed-post being 45 shown in cross-section. Fig. 6 is an elevation of one of the couplings shown at the right hand of Figs. 1 and 2, the side rail being shown in cross-section, the adjusting-bolt not being shown. Fig. 7 is a cross-section 50 through one of the side rails, showing in elevation the clip securing one end of the rigid

cross-bar on said rail and against the coupling.

Having described my invention with reference to the figures illustrated in the drawings, 55 I will now proceed to describe the same with reference to the numerals marked thereon, in which similar numerals refer to corresponding parts in the several views.

In constructing iron beds the one which I 60 have preferably illustrated is constructed by using tubular bed-posts 1, provided with a vertical slot in the wall of the tube, through and into which I insert projecting hook 2 in the crescent face of the hanger for holding the 65 curved surface of the bed-post in the concave recess 3 of hanger-iron 4, which hanger-iron is provided with perforated flange 5, having openings 6 (best illustrated in Fig. 2) for riveting the hanger-iron to the angular side 70 rail, as best illustrated at 77, Fig. 2. It should be understood that I do not limit myself to this form of hanger-iron, as any other hanger-iron may be used which is provided with a perforated flange for riveting or bolt- 75 ing the same to the angle side rails, or it may be otherwise secured to the side rails.

I preferably employ angle side rails each having a horizontal flange 9 and vertical flange 10, Fig. 2. 80

The angle cross-bars 11 are mounted on flange 9 of the side rails. The upper flange of angle cross-bar 11 projects up, as indicated at 12, and the horizontal flanges 13 lie flat on the horizontal flange 9 of the side bars forming a part of the bed-frame. I clamp the wire mattress between the upwardly-projecting flanges 12 of the cross-bars and battens 14, the battens and flanges 12 being suitably secured together, as by rivets 15, which 90 clamp the woven-wire mattress 16 firmly between flanges 12 of the cross-bar and battens 14, so as to hold the same firmly. At one end of the bed I provide a pair of stationary stops 17, which are riveted to the horizontal 95 flange 9 of the side rails, as best illustrated at 18, Fig. 1. I provide rabbeted surface 19, Fig. 2, which fits over the horizontal flange 13 of the angle cross-bar 11 for holding the horizontal flange of said angle cross-bar in a 100 firm position on the horizontal flange 9 of the side rail by means of the rivet and by pro-

- viding a lug 20, Fig. 2, slotted on its inner face to project under the flange 9 of the side rail. By using one of these stops on each side rail at one end of the wire mattress, clamping one cross-bar rigidly against the side rails, said cross-bar is held in a firm position against back 21 of the hanger-iron for keeping the bed in a firm position and preventing the parts from working when the bed is moved.
- 10 At the opposite end of the wire mattress I provide slides 22, carrying the other cross-bar 11, and each slide is provided with slot 23, Fig. 2, constructed to receive horizontal flange 13 of the cross-bar, as best illustrated in the figures before referred to. For maintaining slides 22 in proper position to be moved I provide two lugs, lug 23^a, Fig. 4, and lug 24, same figure. Lug 23^a engages the upper side of flange 9 of the side rails, and
- 15 lug 24 engages the horizontal under surface of the side rails of the flange 9 of said side rails. By this arrangement (the slides on each horizontal flange 9 of the side rails of the bed having the cross-bar inserted in slot 23 of the slides) the cross-bar of one end of the wire mattress can be moved backward and forward on the side rails by means of projecting ears 25, Figs. 1, 2, 3, and 4, and tightening screw-bolts 26, each screw-bolt being inserted
- 20 through perforated lug 27, made rigid with the hanger-iron. The screw-threaded end 28 of tightening-bolt 26 is tapped into opening in ear 25 at 28, and by turning the tightening-bolt 26 the slides on each side bar can be
- 25 drawn, carrying with them the movable cross-bar of the bed, to which the woven-wire mattress is rigidly secured, and thereby tightening the mattress to the required degree of tension, the principle being that the bed
- 30 hanger-irons being riveted to the side bars in a fixed position carrying the integral lug 27, connected to the hanger-iron, which is always in a fixed position, and the slide being movable carrying with them the movable cross-

bar permits the woven-wire mattress to be 45 tightened or loosened at the will of the operator. The shoulder 29 on the slide, Fig. 2, operates as a stop for the backward movement of the movable cross-bar of the bed, as best illustrated in Fig. 2. This lug constitutes 50 an integral part of the casting, and a slotted opening for the receipt of horizontal angle of the movable cross-bar should be made sufficiently loose to permit the movable cross-bar to be inserted in the slot in the slides, 55 and as these castings are made of malleable iron the upper flange 30, Fig. 2, may be driven down into close contact with the horizontal flange of the movable cross-bar of the bed for making the parts firm and solid, as 60 illustrated in Fig. 2 of the drawings.

What I claim as new, and desire to secure by Letters Patent, is—

In a bed-frame, the combination of angle-bar side rails provided with end coupling-hangers, each hanger having a flange secured to the vertical flange of a rail, the hangers extending vertically above the horizontal planes of said rails, the hangers at one end of the frame provided with elevated abutments 21, 65 above said rails, angle cross-bars between the ends of said rails and resting directly on the top flanges of the rails, means for adjusting one of said cross-bars longitudinally of said rails, the other cross-bar having its vertical 70 flange held against said abutments of said hangers, and the shouldered clips 17, secured at 18, on the horizontal flanges of said rails inwardly of said bar and projecting under the top flanges of the rails and lapping outwardly over the horizontal flange of the cross-bar, substantially as described.

Signed by me at Utica, New York, this 24th day of September, 1900.

FREDERICK W. WALKER.
